ASSIGNORS, BY MESNE ASSIGNMENTS, TO CAREY & CO., OF PHILADELPHIA, PENN-
SYLVANIA, A FIRM COMPRISING EDWARD REUKAUF AND EDWARD REUKAUF, JR.

SUPPLEMENTAL COVER FOR BOXED GOODS.

1,144,326.

Specification of Letters Patent. Patented June 22, 1915.

Application filed July 18, 1912. Serial No. 710,248.

To all whom it may concern:

Be it known that we, JAMES F. FLAHERTY and CHARLES GERLACH, citizens of the United States, and residents of Philadelphia, Pennsylvania, have invented certain Improvements in Supplemental Covers for Boxed Goods, of which the following is a specification.

Our invention relates to covers designed to protect the contents of boxed goods, such as cigars, from dirt and dust, and also to prevent drying of such goods; and the object of our invention is to provide a suitable supplemental lid or cover which will properly inclose the top of the goods and be so connected to the usual box cover that manipulation of the latter will serve to raise the supplemental lid. Such supplemental lid is of framed glass and is rigidly connected with the ordinary cover without, however, making any change in the latter, and such supplemental cover is readily attachable and detachable to and from such box cover. These and other features of our invention are more fully described hereinafter, reference being had to the accompanying drawings, in which:

Figure 1, is a perspective view of part of a cigar box, partly in section, showing our improved cover connected therewith; Fig. 2, is an end elevation of the hinge portion of the box; Fig. 3, is a similar end elevation showing the box cover tilted to raise the supplemental glass cover and permit access to the box; Fig. 4, is a plan view of a blank from which engaging clips carried by the supplemental cover may be formed; Fig. 5, is a perspective view of the finished clip before attachment to the frame of the supplemental cover, and Fig. 6, is a view of a modified structure within the scope of our invention.

In the drawings, 1 represents a cigar or similar box for containing goods to be vend-
ed, and 2 a suitable metal frame, which may have flange 3 fitting down over the front and sides of the box, and is grooved at 4 on all four inner sides to receive a sheet of transparent material, preferably glass, indicated at 5; the whole forming a supplemental cover or lid. The frame is provided with means for attachment with the box cover 6, comprising clips for engaging the ends of the same; said clips having portions 7 and

8 bent around to form substantially parallel- 55
ing walls and providing guiding means whereby the supplemental cover may be connected with the box cover; a foot portion 9 whereby the clips may be secured to the frame, and a portion 10 forming a rib which 60
is bent up in the manner indicated and may be secured to the wall 11 connecting the walls 7 and 8. The clips may be soldered or brazed in place or otherwise fastened to the frame. 65

The supplemental cover may be heavy enough to hold the cigar box cover in the elevated position, as illustrated in Figs. 1 and 2, of the drawings, and such supplemental cover may be readily lifted by tilting the box cover on its usual hinge, indicated at 12, as indicated in Fig. 3. 70

As will be noted, the clip is made of one piece, substantially in the form indicated in Fig. 4, which is bent on the dotted lines 75 to the shape shown in Fig. 5; the portion forming the rib 10 being then soldered or otherwise secured to the wall 11 of the clip before attachment to the supplemental frame. 80

The flange 3 renders the cover dust-proof and substantially air-tight so that when employed with cigar boxes the cigars will keep fresh and retain their desired moisture. If desired, the flange may be omitted and in 85 such instance the cover will fit between the end walls of the box as indicated in Fig. 6; the front edge of the same lying on the front wall of the box.

In order that the supplemental cover 90 structure may be employed as an advertising or indicating device, we may place a plate 13 between the clips, as clearly indicated in Fig. 1, which plate may carry the name of a cigar, for instance, together with 95 its price, or the price alone, or any advertising matter or indicia. This plate could be formed integral with the clips. In either instance, it serves as a spacer as well as stiffening means for said clips. 100

Although we have referred to the use of glass as the transparent material for the supplemental cover, it will be understood that any suitable transparent material may be employed. 105

We claim:

1. The combination of a metal frame carrying a sheet of glass, and clips carried

by said frame for engagement with the ends of a box lid, said clips comprising a pair of paralleling vertical walls connected by an end wall, a horizontal portion at right angles to the vertical walls and permanently secured to the frame, and a stiffening rib bent up from the horizontal portion and connected to the vertical end wall.

2. A supplemental cover for boxed goods, 10 cigars and the like, comprising a frame, up-standing clips rigidly fixed to said frame and disposed substantially at right angles thereto for engagement with the ends of a box lid, said clips comprising paralleling 15 vertical walls connected by an end wall and designed for engagement with and to support the box lid in a fixed position with relation to the frame, and a transparent plate carried by said frame and overlying the contents of the box.

3. The combination, in a display cover for boxes having hinged lids, of a metal frame grooved at its inner edges, a glass plate carried by the grooved portion of the frame, 25 and clips rigidly connected to said frame and upstanding from the upper surface of the same for embracing the edges of the box, said clips serving to hold the lid in definite position with relation to the frame and

rendering the latter movable with said lid 30 on its hinged connection with the box.

4. The combination of a metal frame, a sheet of glass carried thereby, clips carried by said frame comprising connected paralleling walls vertically disposed and adapted 35 to embrace the ends of a box lid, and a stiffening rib integral with said clip, said rib being bent up from a portion of the clip overlying the frame and secured to one of the vertical walls of the same.

5. The combination of a metal frame, a sheet of glass carried thereby, clips carried by said frame comprising paralleling walls vertically disposed and adapted to embrace the ends of a box lid, stiffening ribs integral 45 with said clips and secured to one of the vertical walls of the same, and a plate connecting said clips and spacing and bracing the same.

In testimony whereof, we have signed our 50 names to this specification, in the presence of two subscribing witnesses:

JAMES F. FLAHERTY.
CHARLES GERLACH.
